TIME DELAY DEVICE

Anthony Van Ryan, Ocean Springs, Miss., and Kazuo Henry Date, South Milwaukee, Wis., assignors to McGraw-Edison Company, a corporation of Delaware

Original application September 25, 1953, Serial No. 382,365, now Patent No. 2,810,038, dated October 15, 1957. Divided and this application November 29, 1954, Serial No. 471,572

2 Claims. (Cl. 317—178)

This invention relates to time delay devices for circuit interrupters.

This application is a division of our copending application Serial No. 382,365, filed September 25, 1953, now Patent No. 2,810,038, for Circuit Interrupter assigned to the same assignee as the present application.

In circuit interrupters, time delay devices are employed to secure delay in the operation of the circuit interrupter under various conditions. Among others is the two time current type of circuit interrupter in which the circuit interrupter responds to the overload either substantially instantly or after a delay period as described in greater detail in our above noted copending application.

Objects of this invention are to provide a novel form of time delay device which may be easily applied to circuit interrupters and which may be instantly changed from a quick response device to a delayed response device so as to secure the two time current characteristics of a circuit interrupter.

Further objects are to provide time delay devices in which the response of the device may be changed from a quick response to a delayed response by control means actuated in any suitable manner as for example, through the agency of counting means as set forth in greater detail in our above noted application and in which this control means is located externally of the time delay device.

Further objects are to provide a time delay device which is so made that it may be adjusted for an inverse relation to the magnitude of the overload or may be adjusted so as to have a definite or predetermined force exerted on the time delay device whose value is independent of the value of the energizing current for operating the time delay device.

Further objects are to provide a time delay device which is adapted to operate a tripping device and which is arranged to be adjusted to cause tripping to occur at any desired point during the tripping stroke of the time delay device so as to secure a very gradual and accurate and fine adjustment to determine the exact value of the time delay before tripping will occur.

Further objects are to provide a time delay device which is so made that means are provided for locking the parts in their several positions of adjustment.

Embodiments of the invention are shown in the accompanying drawings in which:

Figure 1 is a sectional view of one form of the time delay device and the tripping means.

Figure 2 shows a modified form of time delay device.

Figure 3 shows the modified form of Figure 2 in another position of adjustment.

Referring to the drawings it will be seen that the first form of the time delay device is shown in Figure 1 and it consists of an electromagnet having its body portion indicated generally by the reference character 10. This body portion surrounds the magnet coil 11 and a movable sleeve-like magnetic plunger 12 is slidable into the coil

2

11 when such coil is energized. A rod 13 extends downwardly through the magnetic plunger 12 but is not attached to the plunger. A spring 14 is positioned within the upper portion of the plunger 12 and is positioned between the nut 15 screwed on the upper end of the magnetic plunger 12 and a shoulder or collar 16 formed on the rod 13. It is thus apparent that when the plunger 12 is drawn downwardly towards the stationary lower pole piece 17 that it will compress the spring 14 and urge the rod 13 downwardly.

The lower end of the rod 13 is rigidly connected with the time delay piston 18 which is slidable within its cylinder indicated at 19 which cylinder is a unitary part of the body portion of the time delay device or trip unit. The upper end of the cylinder 19 is normally in communication with the lower end of the cylinder by means of the ducts 20 and 21 and the hollow sleeve-like member 22 whose lower end constitutes a valve seat for the upwardly spring pressed valve 23, the spring being indicated at 24. Normally, the valve 23 is held in the open position for the fast shots but is allowed to rise and seat against the lower end of the sleeve 22 and thus stop communication between the ports or passages 20 and 21. When this occurs the piston 18 is delayed as the upwardly closing valve 25 has closed the opening 26 in the lower end of the piston 18. This disk or valve 25 is provided with a small hole 27 which allows fluid to flow through the piston to the upper portion of the cylinder 19 when the piston is depressed, and when the valve 23 is closed.

The magnetic plunger 12 is urged upwardly by means of the spring 28. The stress or compression of the spring 28 may be adjusted by means of the nut 29 to determine the point of overload or current value at which the plunger 12 will move downwardly.

The upper end of the rod 13 is threaded and receives the spool-like member 30 which operates the lever 31 carried by the rockshaft 32. The rockshaft 32 rigidly carries a semicylindrical latch member 33 which normally restrains the upper end of a trip finger 34 of latch means or releasing means which is described in detail in the above identified application. The position of the spool-like member 30 on the rod 13 will determine the amount of overlap between the finger 34 and its coacting semicylindrical member 33 and will thus determine the point during the downward travel of the magnetic plunger 12 at which release of the finger or lever 34 will occur. The rockshaft 32 thus controls the tripping of the main switches as described in the above identified application.

It is to be noted also from Figure 1 that the valve 23 is controlled by the rod 35 which in turn is controlled by means of a cam 36 operatively carried on a rockshaft 37. The cam 36 bears against the lever 38 which controls the position of the rod 35 and consequently of the valve 23. The cam 36 is not directly connected to the rockshaft 37 but is connected directly to a small lever 39, rigid with the rockshaft, by means of a pin 40 which may be selectively positioned in any one of a plurality of holes 41 formed in the cam 36. The purpose of this is to provide an adjustment between the cam 36 and the lever 39 to determine the relative number of fast and slow operations of the time delay device which may be used for any purpose, but which, in the prior application, hereinabove identified constitutes a ground trip for tripping the main switches. The lever 39 which is rigid with the rockshaft 37 of the cam 36 is connected to the sequence bar 42 so that the position of the cam 36 is determined by the position of the sequence bar.

It is to be noted that the spool-like member 30 is provided with a plurality of slots 43 into any one of which a locking pin 44 may extend to thus lock the spool-like member 30 in its adjusted position on the rod 13.

It is to be noted that the relative position of the semi-cylindrical latch 33 and the trip lever 34 may be adjusted by screwing the sleeve-like member 30 upwardly or downwardly on the rod 13 on which it is screwed. The pin 44 is of course withdrawn during this adjustment and is reinserted after the adjustment has been made.

As the force due to the downward pull of the magnetic plunger 12 is transmitted through the spring 14 it is apparent that as soon as the current through the coil 11 reaches a predetermined value that the plunger will execute its full stroke and fully compress the spring 14. The spring 14 will thus urge the plunger downwardly with a definite or predetermined force independently of the value of the energizing current through the coil 11. The term "definite" as here used is intended to indicate this condition.

It is also apparent that the adjustment of the nut 29 will determine the value of the current necessary to cause downward motion of the plunger 12.

The cam 36 constitutes an externally located control device so that it may be moved from one adjusted position to the other to thereby make the time delay device function rapidly or in a delayed manner.

It is clear also that no matter how heavy a current flows through the coil 11 no damage will be caused the tripping device since the force of the downward stroke of the plunger 12 is transmitted through the spring 14 to the trip or latch means and the force thus transmitted cannot exceed a predetermined amount. Further the adjustment of the nut 29 determines the value of the current flowing through the coil 11 at which downstroke of the magnetic plunger 12 occurs. These two adjustments may be made independently of each other.

In the second form of the invention shown in Figures 2 and 3, the rod 13', which corresponds to the rod 13 of Figure 1, is extended at its threaded upper portion. At its threaded upper portion it is provided with a fixed member 50 screwed thereon which adjustably receives the nut-like member 49 which is integral with the spool-like portion 51 corresponding to the spool-like portion 30 of Figure 1. The portion 50 of Figure 2 is locked to the rod 13' by means of a pin 52 extending into any one of a plurality of slots 53 formed in the member 50.

In Figures 2 and 3, it will be noted, that the spool-like member 51 may be adjusted on the member 50 to any desired position and temporarily locked in such position by means of the spring finger 54 carried by the member 50. It is clear that if desired, numbers may be provided on the portion 49 of the spool-like member 51 to indicate its position of adjustment. Such numbers are not shown on the drawing.

In the form of the invention shown in Figures 2 and 3, the rod 13' rigidly carries a small washer 45. The washer 45 therefore constitutes a second shoulder on the rod 13'. The rod 13' also slidably carries a nut 46 which may be screwed onto the threaded upper portion 47 of the magnetic plunger 12'. Under these conditions downward motion of the plunger 12', see Figure 2, will cause the piston 18, see Figure 1, to move downwardly without the intervention of the spring 14 and consequently the tripping means or time delay means will operate inversely with reference to the current flowing through its energizing coil. However, when it is desired to have the tripping means or time delay means, in its modified form shown in Figures 2 and 3, operate in the same manner as the tripping means or time delay means shown in Figure

1, the nut 46 is unscrewed and is slipped upwardly along the rod 13', until the spring fingers 48 yieldingly grip the nut 46 as shown in Figure 3.

It is to be noted also that the relative position of the semicylindrical latch 33 and the link 34 of the latch means may be adjusted by screwing the nut 49 upwardly or downwardly on the member 50, two different adjustments being shown in Figures 2 and 3.

It will be seen that novel time delay or trip means has been provided which may operate in a definite manner or with a predetermined force independently of the value of the overload.

It will also be seen that the time delay device may be instantly changed so that it operates inversely as the value of the overload increases.

Further, it is to be noted that in either form of time delay device, the device may be quickly changed, from a slow acting to a quick acting time delay device, or vice versa, and that this changeover is effected by externally located control means.

Although this invention has been described in considerable detail, it is to be understood that such description is intended as illustrative rather than limiting, as the invention may be variously embodied and is to be interpreted as claimed.

We claim:

1. A time delay device for a circuit interrupter comprising a body portion having a cylinder formed therein adapted to contain a fluid, a piston in said cylinder, a piston rod, said device having an escape opening, a magnetic plunger slidably on said rod, a coil surrounding said plunger, a first member removably carried by said plunger, a second member carried by said rod, a spring interposed between said first member and said second member whereby a definite force is transmitted to said piston irrespective of the magnitude of the current flowing through said coil, and means including said first member for selectively locking said plunger to said rod whereby an inverse time current relation is secured, or for releasing said plunger from direct connection to said rod.

2. A time delay device for a circuit interrupter comprising a body portion having a cylinder formed therein adapted to contain a fluid, a piston in said cylinder, a piston rod projecting from said body portion, a magnetic plunger slidably carried by said piston rod, a coil surrounding said plunger, said plunger having a recessed outer end provided with an annular inwardly projecting shoulder, said piston rod having a collar located within the recessed portion of said plunger, a spring interposed between the annular shoulder of said plunger and the collar of said piston rod, said piston rod having a second collar located outwardly of the annular shoulder of said plunger and rigidly attached to said piston rod, and a nut removably screwed on the outer end of said plunger to selectively clamp the second collar of said piston rod to said plunger when said nut is screwed on said plunger, or to release the second collar of said piston rod from said plunger when said nut is unscrewed from said plunger.
